COSMETIC DISPENSER

James Victor Kamp and Thayer S. Damon,
Salem, Ill.

Application October 2, 1946, Serial No. 700,716

6 Claims. (Cl. 222—386)

1

This invention relates to dispensers for cosmetics, familiarly known as creams or pastes, such for example as face creams, and in particular to a device in the nature of a compact which may be readily and safely carried in pocketbooks, handbags, toilet kits, and the like.

A general object of the invention is to provide an attractive article of the nature described comprising a cap section having a dispensing opening and a base section, both sections including cooperating elements for expelling a creamy substance through the dispensing opening when one section is rotated relative to the other. While devices of this general nature have been heretofore proposed, nevertheless, they have not come into general use because they frequently leak or the parts accidentally become separated to spill or expose the contents.

Accordingly, one of the objects of the invention is to provide a container construction which lends itself to convenient manufacturing practices, and includes mating sections having cooperating means for being interlocked by mere assembly and partial rotation, as well as effective means for sealing the sections after they are once assembled and relatively rotated to compress and expel the contents.

Another object is to provide simple and reliable means for locking the sections against being returned to their original point of assembly so that they cannot come apart or be separated for refilling.

A further object is to provide a construction which includes a minimum number of parts thereby making a dispenser which is economical to manufacture and reliable in use.

With the above and other objects in view which will more readily appear as the nature of the invention is better understood, the same consists in the novel construction, combination, and arrangement of parts, hereinafter more fully described, illustrated and claimed.

A preferred and practical embodiment of the invention is shown in the accompanying drawings, in which:

Figure 1 is a perspective view of the improved dispenser.

Figure 2 is a side elevation of the cap section.

Figure 3 is a bottom plan view of the cap section.

Figure 4 is a top plan view of the base section.

Figure 5 is a transverse cross-section of the assembled dispenser taken on the line 5—5 of Figure 4.

Figure 6 is a top plan view of the bottom sec-

2

tion showing the piston vane moved away from its initial position, and as it would appear after having expelled a portion of the contents.

Figure 6a is a detail plan view of the base partly in section showing how the piston vane may be made integral with the cap while the abutment is made integral with the base.

Figure 7 is a perspective view of a modified form of the invention.

Similar reference characters designate corresponding parts throughout the several figures of the drawing.

Referring first to the embodiment of the invention shown in Figures 1 to 6, inclusive, it will be observed that the same essentially includes in its organization a cap section A and a base section B, respectively including side walls 1 and 2 adapted to be interfitted in telescopic relation, and each being provided externally with indexing ribs 3 and 4 or their equivalent to facilitate initial assembly and subsequently serve as a signal to indicate the contents remaining in the container after use has once been started. The said indexing elements are aligned to effect initial assembly and after partial rotation of the sections never return to this relation because of locking means hereinafter described.

The cap section A is provided with a dispensing opening or hole 5 radially aligned with the indexing element 3 and located in a finger-receiving depression or well 6. The under face of the cover A is also provided with a downwardly projecting pin 7 which is angularly off-set with respect to the hole 5 as shown in Figures 2 and 3 and intended to engage with the hook portion 8 of a radially disposed piston vane 9 which is formed at its inner end with an eye 10 for fitting over a post 11 axially carried by the interior face of the base 2. The vane 9 therefore, can rotate relative to the base. Said base B is also provided with an integral radially disposed abutment 12 in the form of a wall which, like the piston vane 9, is coextensive in height with the space between the inner surfaces of the cap and base. It will also be noted that the length of the vane 9 and the abutment 12 are substantially the same so that when considered in connection with the post 11, completely span the radial distance between the post and interior face of the side walls 1 and 2 of the cap and base. When the pin 7 is engaged with the hook 8 of the vane it will be apparent that relative rotation of the cap A to the base B will cause movement of the vane 9 with respect to the abutment 12 so that the material M (Figures 4 and 6) will be expelled

through the discharge opening or hole 5 into the well 6 of the cap as indicated at M' in Figure 1. The hole 5 and pin 7 being in angular relationship, and the hole 5 being disposed relatively in advance of the pin when the pin 7 is engaged with the vane 9, the latter will, of course, when moved by the pin, cause the material in front thereof to pass through the opening 5 since the material M is trapped in the space between the cap and base against the abutment wall 12.

Referring now more particularly to the means of holding the sections A and B together for rotary movement as well as against separation, it may be first noted that the vane 9 preferably carries a locking element 13 in the form of a light leaf spring which is secured at one end to the related face of the vane 9 while its opposite yielding end engages the inner face of the side wall 2 of the container. This spring 13 is intended to cooperate with a locking element 14 in the inner face of the side wall 2, and which, in the example shown, is in the form of a notch formed in the side wall to provide a locking shoulder 15. Obviously, however, instead of making the locking element in the form of a notch depressed into the side wall of the base, it may be in the form of a raised tooth with the same general locking effect.

The inner face of the side wall 1 of the cap A is provided with the diametrically disposed pairs of ribs 16 and 17. These ribs are intended to pass through corresponding pairs of notches 16a and 17a in the upper flange portion 18 of the base, said flange portion 18 having its outer face provided with an annular recess or channel 19 whose upper side wall constitutes an abutment or track against which the pairs of ribs 16 and 17 bear when the sections A and B are rotated relative to each other.

As previously indicated, the ribs 16 and 17 which cooperate with the notches 16a and 17a on the base are so related to the indicator ribs 3 and 4 that, when said ribs are in vertical alignment as shown by the dotted line and solid line positions of 3 and 4, respectively, in Figure 1, the ribs 16 can readily enter their related notches 16a in the base. Likewise, when the sections A and B are thus assembled the pin 7 engages the hook 8 of the vane 9. Upon moving the cap A in the direction of the arrow shown in Figure 1, the said sections A and B not only become interlocked for further rotary movement to perform the operation of expelling the contents with the aid of the elements 9 and 12; but, also, the spring locking element 13 is moved sufficiently so that it passes beyond the locking element 14. Once the sections A and B are initially rotated relative to each other, continued rotary movement between the same is possible until the contents of the dispenser have been exhausted. Of course it is possible to rotate the elements A and B so that the vane 9 may idly move back substantially to its original position. However, due to the spring leaf 13 and locking element 14, it will be impossible to bring the ribs 16 and 17 back into registering relation with notches 16a and 17a. Thus, after the parts have been once assembled and a portion of the expelling movement of the vane has taken place, it will be impossible for the sections to be subsequently separated for the purpose of effecting a refill of the material.

Another distinctive feature of the construction shown in Figures 1 to 6 is that the cap A and base B are provided with suitable sealing means to prevent the escape of the paste or cream un-

der pressure. In the example shown this sealing means preferably consists of an annular collar 20 on the inner face of the cap and spaced inwardly from the side wall of said cap so as to fit in a complementary recess 21 in the flange 18 of the side wall 2 of the base.

In the construction shown in Figures 1 to 6 inclusive, the sections A and B having the characteristics described are preferably made from plastic material so that they can both be readily made by a convenient stamping, molding, or pressing operation. The parts A and B together with the piston vane 9 constitute all of the movable parts of the device. Thus, the simplicity of the invention from the standpoint of manufacture and use becomes apparent.

Figure 6a illustrates a modification of the invention above described wherein the piston vane 9a is made integral with the cap section A, and the abutment 12a is likewise made integral with the base section B. It will also be observed that the post 11a and abutment 12a may be integrally formed or connected so that the piston vane 9a carried by the cap section A may exert adequate pushing force against the contents of the container with respect to the abutment and post. In this form of the invention all of the means for interlocking the cap and base previously described are adhered to. The difference between the construction shown in Figure 6a and that shown in Figure 6 is that the movable vane 9 of the latter figure is made integral with the cap section thereby eliminating the metallic vane as a separate element, and likewise, the locking means 13, 14, 15 of Figure 6 is omitted from the construction shown in Figure 6a.

A modification of the invention is shown in Figure 7 wherein the device may be made of transparent plastic material and cap section A' and the base section B' have their side walls 1b and 2b telescopically interfit, while the base section B' is interiorly provided with an integral abutment wall 12b and the cap section A' has integrally formed therewith the piston vane element 9b. In this form of the invention the cap section A' is formed with a dispensing or discharge hole 5a, and the piston vane 9a as well as the abutment wall 12b terminate at their inner ends at a point short of a central pivot element 22 for pivotally connecting the sections together. This pivot element may assume various forms but preferably consists of a tubular shell having a head portion at one end for engaging the outer face of one of the sections while its hollow interior is threaded to receive a cap screw 23 whose head engages the outer face of the base. Thus, the pivot 22 serves as a fastening for holding the sections A' and B' against accidental separation. In this arrangement the base section B would be filled with cream or paste and the piston vane 9b and abutment wall 12b assembled in juxtaposed relation so that, as relative movement occurs between the sections on the element 22 as an axis, the movement of the vane relative to the abutment will expel the material through the discharge opening 5a. In this form the inter-engaging means on the cap and base as per Figures 1 to 6 inclusive is unnecessary because of the fastening 22.

From the foregoing it will be apparent that the invention provides a container for creamy or pasty material from which the same may be dispensed in the form of a cylindrical ribbon through the cap section, as desired, thereby making it possible readily to obtain a small amount

of the material in a convenient way, while at the same time preserving the remaining contents for future use.

Without further description it is thought that the advantages of the invention will be readily understood by those skilled in the art and will, of course, be apparent that changes can be resorted to within the scope of the appended claims.

We claim:

1. A dispenser for creams and the like, comprising, annular cupped cap and base sections constructed for telescopic mating engagement, radially disposed abutment means movable with each section, said cap section having a dispensing hole, whereby, relative rotation of the sections cause the cream trapped between opposite sides of the abutment to be forced through said opening, and means adapted to prevent reverse rotation of the cup after the initial dispensing operation.

2. A dispenser for creams and the like, comprising, annular cupped cap and base sections, said cap section having a dispensing opening, a pin carried by the inner face of the cap section, side walls on the sections for telescopic engagement and having interengaging lug and recess means indexed for registry to effect initial assembly and adapted upon relative rotational movement of the sections to hold the same together, an abutment on the base section, a piston vane pivoted to the base, means for connecting the piston with the pin on the cap section at a point behind the hole in the cap, whereby, relative rotation between the cap and base to move the piston toward one face of the abutment compresses the contents of the dispenser to discharge a portion thereof through a hole in the cap, and means adapted to prevent reverse rotation of the cup after the initial dispensing operation.

3. A dispenser for creams and the like, comprising, annular cupped cap and base sections, said cap section having a dispensing opening, a pin carried by the inner face of the cap section, side walls on the section for telescopic engagement and having interengaging diametrically disposed lug and notch means indexed for registry to effect initial assembly and adapted upon relative rotational movement of the sections away from the point of registry to hold the same together, an abutment on the base section, a central post on the base section, a piston vane pivoted to said post, a hook on the vane for receiving the pin on the cap, and cooperating means respectively carried by the piston vane and on the inner face of the side wall of the base for preventing rotation of the cap and base sections back to their point of initial assembly and thereby lock the sections against axial separation until one rotation of the cap has been completed to discharge the cream.

4. A dispenser for creams and the like, comprising, annular cupped cap and base sections, said cap section having a dispensing opening, a pin carried by the inner face of the cap section, side walls on the sections for telescopic engagement, opposite pairs of spaced lugs formed on the inner face of the side wall of the cover section, a flange formed on the base section inwardly of

the outer face of the side wall of said section and having an annular groove therein, the portion of the flange between the groove and the top edge thereof being provided with opposite pairs of notches for receiving the corresponding pairs of lugs on the cover, indexing elements on the outer face of the side walls of the cap and base for visually indicating when the said lugs on the cap and said notches on the base are in alinement to permit initial assembly of the sections, a radially disposed abutment wall carried by the base, a piston vane pivotally mounted on the base, a hook formed on said vane and means on the cover for engaging said vane and said hook to move the same relative to said abutment wall, and cooperating means on the piston vane and the inside face of the side wall of the base for preventing the sections returning to the point where the lugs and notches register, whereby separation of the cap and base sections is prevented until one complete revolution of the cap is completed.

5. A dispenser for creams and the like, comprising, annular cupped cap and base sections, said cap section having a dispensing opening, telescopically interfitting side walls on the cap and base sections, a sealing recess formed at the upper edge of the inner face of the side wall of the base, an annular sealing flange carried by the cap for fitting into said recess, an annular track formed in the sidewall of the base, cooperating means on said side walls of the cap for interlocking with said track formed in the base section, a fixed abutment carried by the base, a radially disposed piston vane pivotally carried by the base, and means on the cover for engaging said vane.

6. A cosmetic dispenser, comprising, cap and base sections, said cap section having a dispensing opening and said base section having an annular groove, mating lug and notch means respectively on the cap and base adapted to interfit to assemble the sections and of a depth to permit the lugs to ride in the groove upon relative rotation of the sections, lock means associated with the cap and base to prevent the return thereof to the point of initial assembly so that the lug means cannot be removed from the groove means to effect separation of the sections until a complete revolution of the cap has been finished to prevent refilling of the dispenser, and vane and abutment means on the cap and base sections for compressing the contents of the dispenser and cause the same to pass through the dispensing opening of the cap.
